UNITED STATES PATENT OFFICE.

MARK ANTHONY, OF SAN FRANCISCO, CALIFORNIA.

STATION-INDICATOR.

SPECIFICATION forming part of Letters Patent No. 325,643, dated September 8, 1885.

Application filed June 18, 1884. (No model.)

To all whom it may concern:

Be it known that I, MARK ANTHONY, a citizen of the United States, residing at San Francisco, in the county of San Francisco and 5 State of California, have invented certain new and useful Improvements in Station-Indicators for Railroad-Cars, to indicate the names of stations, intersecting streets, or points of stoppage, the whole being arranged in a box 10 having a glass front and having a bell or gong operated by indicating mechanism to sound an alarm, of which the following is a specification.

Referring to the accompanying drawings, 15 forming a part of this specification, Figure 1 is a rear elevation of my improved station-indicator. Figs. 2, 3, 4, 5, 6, 7, 8, 9, and 10 are detail views, which will be more fully explained hereinafter.

20 Similar letters of reference are used to indicate like parts throughout the several figures.

A represents the inclosing box or frame, having a glass front or door, within which the 25 main portion of the indicating apparatus is placed.

B B are two vertical shafts, placed near each end of the containing-box and secured in suitable end bearings, C C, and braces D, 30 as shown in Fig. 1.

Upon the upper portion of the shafts B are keyed the reels or drums E E, upon which the indicating-ribbon F, having the names of the stations thereon, is wound.

35 One of these drums is provided upon the face of the lower head with downwardly-projecting lugs or detents G, which engage with a prong, H, extended from the spring-rod I, upon the lower end of which the bell J is 40 secured.

The top ends of the ribbon reels or drums closely approach the top of the containing-case, and such upper ends are engaged by the brakes K, which consist of a piece of spring-45 steel screwed by one end to the top of the containing-case, and provided at the other end with a pad or brake-shoe of leather or india-rubber, which the action of the spring presses down upon the drum's head, thus preventing undue motion being given to the drums when being operated. The degree of pressure of these spring-brakes is regulated

by the pressure-screws L L, let into the top of the containing-case and operated from the outer side thereof.

Upon the floor of the containing-case I secure journal-bearings M M, carrying the horizontal shaft N, upon which are keyed the bevel-gears O O, facing in opposite directions and arranged to mesh with the beveled pinions P P, keyed upon the vertical shafts B B beneath the lower head of the ribbon reels or drums.

It should here be remarked that the horizontal shaft, its beveled gears, and journal-boxes are interposed or situated between the two vertical drum carrying shafts, as shown in Fig. 1.

Upon one end of the horizontal shaft I form a shoulder or collar, Q, which is engaged by the clutch R, into the base of which a thumb or set screw, S, is tapped. This screw passes through a fixed collar, T, in one end of the containing box or case, and the outer end thereof is provided with a milled head for convenience in adjusting, as it will be readily seen, from an inspection of Figs. 1 and 2, that by turning the screw to the right or left hand the clutch R is advanced or retracted, and by engaging the collar Q or bearing against the side of the adjacent gear O, as the case may be, causes the shaft to which it is attached to move endwise and cause the gear-wheels upon the end of said shaft to engage with either one of the two pinions P P.

At any convenient point on the shaft N between the bearings thereof I key the pin-wheel U, the pins V of which are engaged by a pawl, W, carried by a vibrating frame-work, X, journaled on the shaft N and working 90 through a guide, Y, secured to the base of the containing-case.

The pawl is kept in constant contact with the pins V, by means of a flat spring, Z, fastened by its lower end to the pawl-carrying frame, and the pawl-carrying frame is kept in its depressed position, as shown in Fig. 5, by means of a coiled spring, A', which is attached by one end to said frame-work and by the other end to the floor of the containing-case.

To the extremity of the pawl-carrying frame I attach a length of coiled spring, B', to which is in turn attached a cord, C', leading over a

pulley, D', fixed to the top of the containing-case, and thence down through a tube, E', through the floor of the case, and is connected to the spring-rod F', (shown in detail in Fig. 4,) secured in a collar, G', attached to any suitable timber, H', beneath the floor of the railway or other car, as shown in Fig. 1.

The spring rod or bolt F' extends some distance above its sustaining-collar, and is provided with a head, I', between which and the top of the collar is coiled an expansive spring, J', which keeps the spring-bolt in its elevated or normal position. The lower end of the spring-bolt is slotted, as shown in Fig. 4, to receive the upper end of the shank K', which is pivoted therein. The upper forward corner of this shank is rounded off, so that the shank may be bent or turned upward when it becomes necessary to remove the car from the railway, or so as to readily pass over obstructions when the car is going backward. Yet when the car is going forward the squared upper rear corner or shoulder of the shank engages with the squared slot in the spring-bolt, and the whole is held perpendicularly rigid.

As this device is intended more particularly for use upon cars operated by endless cables moving in a tunnel-way between the tracks and employing a grip passing from the car through a central slot down to the operating-cable, I extend the aforesaid shank K' down through the grip-slot, and attach to one side of the shank a horizontally-projecting friction-roller, L', which ordinarily travels along or through the tunnel-way close to the under side of one of the slot-rails M', as shown in Figs. 1, 9, and 10.

In order to produce an automatic operation of the indicating mechanism, I attach to the under side of the slot-rails, or at any convenient place within the tunnel-way, a downwardly-extending incline or wedge N', (seen in side elevation in Fig. 10,) down the edge of which the friction-roller L' travels until the greatest depth of the incline is reached, (see Fig. 9,) when it glides off on the abruptly-curved base of the triangular figure formed by the wedge, and the roller resumes its original position close beneath the slot-rails.

The operation of my improved automatic station-indicating device will be as follows, to wit: Supposing that the car is about to start upon a trip to the opposite terminus of the road, and that the ribbon F is all wound upon one of the reels or drums E, the operator now operates the clutch-screw S to slide the shaft N length or end wise and bring one of the bevel-gears O into mesh with the beveled pinion P, situated upon the shaft of the empty reel, as seen in Fig. 1.

As the car travels forward and approaches a station or intersecting street the shank K' and its roller will engage with the incline or wedge N', which will draw down the spring bolt F', compressing the spring J', and, by means of the connecting-cord C', spring B',

and pulley D', will cause an uplifting of the pawl-carrying frame-work X and produce a partial rotation of the pin-wheel U, which motion is communicated through the shaft N and bevel-gearing O P to the winding reel or drum, and the name of the next street or station on the ribbon F is brought into view, while at the same time an alarm is sounded upon the bell or gong. As soon as the onward motion of the car carries the shank K' past the butt-end of the wedge or incline the expansive spring J', coiled around the stem of the spring rod or bolt F', will cause it to shoot upward or back to its original position, while the coiled spring A' will draw down the pawl-carrying frame X to its original position, and the parts will be in position to repeat the same movements when the incline N' near the next station is approached.

In Figs. 7 and 8 I have illustrated a modification of the spring-rod F', the collar G' being slotted at one side for the reception of a guide-pin on the rod F', while the spring J' is arranged within the collar or tube G', instead of above it, and so exerts a downward pressure on the rod F' that causes it to carry the roller L' down on the track or level surface after it has passed over the incline. This modified form is intended for use in connection with an upwardly-inclined wedge or incline, whether said wedge be placed upon the surface of the road-bed or at the bottom of the tunnel-way.

When the modified form of spring-rod and collar is employed in connection with an upwardly-inclined wedge, N', the cord C', pulley D', and spring B' will be dispensed with, and the upper end of the rod F' will be connected directly to the vibratory frame X for the purpose of giving it the necessary upward movement to actuate the pin-wheel U, shaft N, and winding-drums, as before described.

It should here be observed that I do not desire to confine myself to the exact means herein set forth for operating my device, as various methods may be adopted for tripping the spring rod or bolt F', such as a pin or projection placed at any point in the tunnel-way so as not to interfere with the cables or cable-gripper bars.

Having thus described my invention, what I claim, and desire to secure by Letters Patent, is—

1. In an automatic station-indicator, the combination of the ribbon-reels E E, one of which is provided with lugs or detents G G, the spring-rod I, having prong H, and the bell J, secured to said rod, substantially as described.

2. In an automatic station-indicator, the combination of the shafts B B, carrying ribbon-reels E E and pinions P P, the intermittently rotary shaft N, having collar Q and carrying bevel-gears O O, the clutch R, and the adjusting-screw S, substantially as described.

3. In an automatic station-indicator, the combination of the ribbon-reels E E, mounted

on vertical shafts B B, carrying pinions P P, the horizontal shaft N, carrying bevel - gears O O and having an endwise adjustment to bring either gear O into engagement with its 5 corresponding pinion, the pin - wheel U and vibratory frame X, mounted on the shaft N, and the pawl W, carried by said vibratory frame and adapted to engage the pin - wheel under the pressure of a spring, Z, substantially 10 as described.

4. In an automatic station - indicator, the combination of the vertical shafts B B, carrying pinions P P, the ribbon - reels E E, mounted

on said shafts, the horizontal shaft N, having an endwise adjustment and carrying gears O 15 O, the pin - wheel U, vibratory frame X, carrying pawl W, the springs A' B', cord C', pulley D', spring - rod F', shank K', carrying a roller, L', and the incline N', substantially as describ d.

In testimony that I claim the foregoing I have hereunto set my hand and seal.

MARK ANTHONY. [L. S.]
